COFFEE URN

Jerry Hrabe, Chicago, Ill., assignor to Superior Tea &
Coffee Co., Chicago, Ill.

Filed Apr. 24, 1961, Ser. No. 64,875

Term of patent 14 years

(Cl. D2—3)

FIG. 1

FIG. 2

FIG. 3

FIG. 1 is a front elevational view of a coffee urn, showing my new design;

FIG. 2 shows a side view thereof as seen from the right hand end of FIG. 1, the view from the opposite side being the same;

FIG. 3 is a top plan view; and

FIG. 4 is a rear elevational view.

I claim:

The ornamental design for a coffee urn, substantially as shown.
